UNITED STATES PATENT OFFICE.

JOHN W. DWIGGINS AND LAFE SWANK, OF ANDERSON, INDIANA, ASSIGNORS
TO THE DWIGGINS WIRE FENCE COMPANY, OF ANDERSON, INDIANA, A
CORPORATION OF INDIANA.

DESIGN FOR WIRE FENCING.

SPECIFICATION forming part of Design No. 35,461, dated December 17, 1901.

Application filed October 24, 1901. Serial No. 79,878. Term of patent 14 years.

● *To all whom it may concern:*

Be it known that we, JOHN W. DWIGGINS and LAFE SWANK, citizens of the United States, residing at Anderson, in the county 5 of Madison and State of Indiana, have invented and produced a new and original Design for Wire Fencing, of which the following is a specification.

The accompanying drawing illustrates our 10 design.

The figure is a side elevation of a section of fencing embodying our design.

The essential features of our design are the running-wires 4, each having formed therein 15 a series of kinks 5. Connecting the running-wires is a series of stay-wires, each having a portion 6, which has been grasped at about its middle and wrapped around the adjacent

running-wire. The intermediate portions 7 of the stay-wires are run diagonally between the 20 running-wires from one end of one twisted portion 6 to the other end of the twisted portion on the next running-wire. The intermediate portions 8 extend from one running-wire to another, approximately at right angles 25 thereto, alternately from opposite ends of the twisted portion 6.

We claim as our invention—

The design for wire fencing substantially as shown and described.

JOHN W. DWIGGINS.
LAFE SWANK.
